CLAIM

The ornamental design for a television antenna, as shown and described.

DESCRIPTION

FIG. 1 is a top perspective view for a television antenna showing our new design;

FIG. 2 is a bottom perspective view thereof;

FIG. 3 is a top plan view thereof;

FIG. 4 is a bottom plan view thereof;

FIG. 5 is a left elevational view thereof;

FIG. 6 is a right elevational view thereof;

FIG. 7 is a front elevational view thereof;

FIG. 8 is a rear elevational view thereof;

FIG. 9 is a top perspective view for a television antenna showing a different environment;

FIG. 10 is a bottom perspective view thereof;

FIG. 11 is a top plan view thereof;

FIG. 12 is a bottom plan view thereof;

FIG. 13 is a left elevational view thereof;

FIG. 14 is a right elevational view thereof;

FIG. 15 is a front elevational view thereof; and,

FIG. 16 is a rear elevational view thereof.

The broken lines in the drawings represent portions of the television antenna that form no part of the claimed design.
